UNITED STATES PATENT OFFICE

CHARLES A. ROBINSON, OF SALEM, MASSACHUSETTS, ASSIGNOR TO UNITED SHOE MACHINERY CORPORATION, OF PATERSON, NEW JERSEY, A CORPORATION OF NEW JERSEY

STAPLE FORMING AND INSERTING MACHINE

Application filed April 24, 1930. Serial No. 447,061.

This invention relates to wire straightening devices and is illustrated herein as embodied in a staple forming and inserting machine.

5 Certain staple forming and inserting machines, for example machines of the type disclosed in Letters Patent of the United States No. 1,338,846, granted October 30, 1921, on an application filed in the name of 10 Matthias Brock, include a pair of wire feeding rolls so located relatively to the staple forming and inserting mechanism that the wire from which the staples are formed must be curved through 90° on a relatively short 15 radius between the feed rolls and the staple forming instrumentalities. As the wire used is frequently relatively soft it is necessary to straighten the wire before it reaches the staple forming means and this has been commonly done in the past by passing the wire through a slot or groove the bottom of which is curved in a manner which is effective to take out the curve imparted to the wire by the feed roll. This construction has proved 20 satisfactorily with wire of the sizes commonly handled by such machines. Recently, however, it has been desired to use smaller sizes of wire in some of these machines.

It is accordingly an object of the present 25 invention to provide an improved wire straightening device particularly adapted to handle the smaller sizes of wire (for example wire .02 of an inch or thereabouts in diameter) used for some stapling operations 30 in the manufacture of shoes.

In order to meet varying conditions resulting 35 from different sizes of wire and from the different physical constants of the wire due to differences in its composition, a feature 40 of the invention comprises a tube through which the wire is passed, illustrated herein as located between the feed rolls and the staple-forming instrumentalities of the machine, and means for varying the curvature 45 of the tube to a greater or lesser extent as may be necessary to overcome the curvature of different lots of the wire. As illustrated herein the wire is passed through a flexible, helically wound tube the end portions 50 of which are rigidly supported, the curvature

of the tube being variable by a lever which, after the correct adjustment has been made, is secured against further movement.

With the above and other objects and features in view the invention will now be described with respect to the accompanying drawing and pointed out in the claims. 55

In the drawing,

Fig. 1 is a front elevation, and Fig. 2 is a perspective view of the lower portion of the 60 head of a fastening inserting machine commonly known as a stitch-down staple lasting machine.

The illustrated machine is of the type shown more fully in said Letters Patent of 65 the United States No. 1,338,846. It is provided with a nozzle 10 having a driver passage 12 through which reciprocates a driver 14. A wire indicated at 16 is fed by a pair of rolls 18 through a passage-way 20 to a pair 70 of knives 22, 24 which sever staple lengths from the wire. A horizontally reciprocated inside former 26 and vertically reciprocated outside formers 28 form staples from the wire and present them to the driver passage 12 for 75 insertion by the driver 14 in a work-piece presented to the nozzle 10 in a manner which is well understood by those skilled in this art.

It will be observed that in passing from the feed rolls 18 to the passage 20 the wire 80 16 must be curved through substantially 90°. In order to remove the curvature which this imparts to the wire, and to remove any curvature there may be having any other origin, I have provided a flexible conduit 30 formed 85 from a helically wound wire and rigidly secured at one end to a bracket 32 and at the other end to a block 34 by which the knife 22 is carried.

The conduit 30 can be arranged by adjusting 90 its curvature to overcome curvature previously imparted to the wire. For this purpose a lever 36 is fulcrumed at 38 to the block 34, the conduit 30 passing through an open-ended slot 40 formed in the lever 36. A screw 95 42, passing through a slot 44 in the lever 36 and threaded into the block 34, is effective to hold the lever 36 in adjusted position. When the lever 36 has been placed in a position which gives the conduit 30 the form neces- 100

sary to overcome the curvature of the wire it is left alone until a change in, for example, the size or composition of the wire makes it necessary to have a different adjustment of the conduit.

Having thus described my invention what I claim as new and desire to secure by Letters Patent of the United States is:

1. A staple forming and inserting machine having, in combination, staple forming and inserting instrumentalities, means for feeding wire to the staple forming and inserting instrumentalities, a flexible conduit through which the wire passes after it has left the feeding means and which serves to straighten the wire before it reaches the staple forming instrumentalities, means for flexing the conduit to vary its wire-straightening effect, and means for securing the conduit in its flexed position.

2. A staple forming and inserting machine having, in combination, staple forming and inserting instrumentalities, a pair of feed rolls constructed and arranged to feed wire to the staple forming and inserting instrumentalities, adjustable wire straightening means comprising a flexible conduit located between the feed rolls and the staple forming instrumentalities, and means for securing the flexible conduit of the wire straightening means in adjusted position.

3. A staple forming and inserting machine having, in combination, staple forming and inserting instrumentalities, means for feeding wire to said instrumentalities, a flexible conduit for the wire located between the wire feeding means and the staple forming instrumentalities a portion of which is normally curved, and means for varying the curvature of said conduit adjustable to overcome the curvature of the wire so that each staple length of wire will be substantially straight when it reaches the staple forming instrumentalities.

4. A staple forming and inserting machine having, in combination, staple forming and inserting instrumentalities, a pair of feed rolls constructed and arranged to feed wire to said instrumentalities, a flexible conduit for the wire comprising a helically wound tube located between the feed rolls and the staple forming instrumentalities, and means for varying the curvature of said conduit adjustably to overcome the curvature of the wire so that each staple length of wire will be substantially straight when it reaches the staple forming instrumentalities.

5. A staple forming and inserting machine having, in combination, staple forming and inserting instrumentalities, knife carriers, knives carried by said carriers operable to sever staple lengths from the wire, and a wire straightening device comprising a flexible conduit secured directly to one of the knife carriers and constructed and arranged to

straighten the wire before the successive staple lengths are fed to the position at which they are severed.

6. A staple forming and inserting machine having, in combination, staple forming and inserting instrumentalities, a stationary and a movable knife carrier, knives carried by said carriers operable to sever staple lengths from the wire, and a wire straightening device comprising a flexible conduit carried directly by the stationary knife carrier and constructed and arranged to straighten the wire before the successive staple lengths are fed to the position at which they are severed.

7. A wire straightening device comprising a flexible tube the end portions of which are rigidly supported, and means for controlling the curvature of a portion of the tube between its end portions.

8. A wire straightening device comprising a flexible conduit supported at its end portions, and means engaging a portion of the conduit between its end portions and adjustable to vary the configuration of the conduit.

9. A wire straightening device comprising a flexible tube comprising a helically wound wire, and having its end portions rigidly supported, and means for controlling the curvature of a portion of the tube between its end portions.

10. A wire straightening device comprising a flexible tube supported at its end portions, a lever engaging a portion of the tube between its end portions and adjustable to vary the configuration of the tube, and means for securing the lever in adjusted position.

In testimony whereof I have signed my name to this specification.

CHARLES A. ROBINSON.
